UNITED STATES PATENT OFFICE.

UTLEY WEDGE, OF ARDMORE, PENNSYLVANIA.

METALLURGICAL FURNACE.

1,137,559.

Specification of Letters Patent. Patented Apr. 27, 1915.

Original application filed February 25, 1913, Serial No. 750,596. Divided and this application filed October 22, 1913. Serial No. 796,609.

To all whom it may concern:

Be it known that I, UTLEY WEDGE, a citizen of the United States, residing in Ardmore, Pennsylvania, have invented certain Improvements in Metallurgical Furnaces, the same being a division of my application Serial No. 750,596, filed February 25, 1913, of which the following is a specification.

The object of my invention is to provide for the effective heating of the hearth of a metallurgical furnace by means of an electric current.

In the accompanying drawings I have illustrated the application of my invention to a furnace of the superposed hearth type intended especially for laboratory use and having alternating fixed and rotating hearths, but this is simply for convenience, as my invention is not limited in its application to furnaces of this type.

In the drawings: Figure 1 represents a vertical sectional view of a furnace constructed in accordance with my invention; Fig. 2 a horizontal sectional view on the line *a—a*, Fig. 1; Fig. 3 a transverse vertical section on the line *b—b*, Fig. 2; Fig. 4 a horizontal section of a modified type of furnace, and Fig. 5 a transverse section on the line *c—c*, Fig. 4.

In Fig. 1 of the drawing I have shown a furnace having nine hearths numbered consecutively from top to bottom of the furnace, the hearths 1, 3, 5, 7 and 9 being fixed hearths mounted in the outer wall of the furnace and the hearths 2, 4, 6 and 8 being rotating hearths which are carried by a central shaft 10 mounted in a suitable step-bearing below the furnace and intended to be rotated by any suitable mechanism, preferably of such character that the speed of rotation of the shaft can be changed at will. The furnace may, however, have a greater or less number of hearths than I have shown.

The shaft 10 is preferably hollow so as to permit of the circulation of a cooling medium through it and it is surrounded by relatively short sleeve sections 11 interposed between the successive rotating hearths so as to aid in the support of the same, said sleeves being composed of firebrick, tile, or other heat-resisting material, in order to protect the shaft from injury by the high temperatures which may have to be main-

tained within the working chambers of the 55 furnace.

The outer wall of the furnace is composed of rings 12 of firebrick, tile, or other refractory material, made either in one piece or in sections, and interposed between the 60 successive fixed hearths of the furnace whereby the building up of a furnace structure having a closed casing can be effected expeditiously and with small expenditure of time and labor. In order to restrict as 65 much as possible the radiation of heat from the furnace, the outer wall of the same is provided with a coating or covering 13 of magnesia, asbestos, cement, or other material which is a non-conductor or a poor conductor of heat, and in order that this covering may adhere firmly to the wall of the furnace the rings 12 of the same and also, if desired, the outer faces of the fixed hearths may be roughened, toothed or corrugated, 75 as shown in Fig. 2.

The lowermost of the rotating hearths of the furnace is mounted upon a flange or collar 14 on the shaft 10 and where said shaft passes through the top and bottom fixed 80 hearths it is provided with luted joints 15 to prevent the escape of gas from the interior of the furnace at these points. The top hearth of the furnace may conveniently be used as a drying hearth, the material being fed inwardly over the same by means of rabbles 16 carried by rabble arms 17 secured to and projecting from the upper portion of the shaft 10, the material being fed from the drying hearth 1 onto the first rotating hearth 2 through the upper luted 85 joint 15 and the course of the material in its passage through the furnace being then outwardly on the rotating hearths and inwardly on the stationary hearths, the rotating hearths being less in diameter than the interior of the furnace and the stationary hearths being provided with central openings 18 of greater diameter than the sleeves 11 in order to permit of the 90 dropping of the material from hearth to hearth. In order to provide for such movement of the material over the hearths, rabbles are provided, these rabbles having stems supported in rabble holders which are 95 mounted in openings on the fixed and rotating hearths and extend below the same so that the rabble stems can be readily applied

thereto, the rabbles of one hearth acting upon the material on the hearth below. The specific construction of the furnace and its rabbles, however, forms no part of this invention as it constitutes the subject of my application Serial No. 750,596, filed February 25, 1913, and of which this application is a division.

The present invention relates to electrical means employed for heating certain of the hearths of the furnace and it may be used in connection with ordinary furnaces having superposed fixed hearths or even but a single hearth, in some cases.

In Fig. 1 of the drawing, the electrical heating devices are shown as applied to the hearths 3, 5 and 7. Each of these hearths has sector-shaped recesses or chambers, as shown in Fig. 2, for the reception of electrical resistance blocks 21, each recess being closed at the top in order to provide a continuous upper surface for the hearth but being open below in order that the heat may be radiated from the resistance block directly upon the material carried by the hearth beneath. In order to support each resistance block the recess or chamber in which it is contained may have at each side a flange or shelf 23, or other means of support may be provided as desired. Current can be supplied to the resistance block in various ways so as to effect the heating of the latter by the passage of the current through it. The block may have a hollow core 24 of electrical insulating material for the reception of the wire from one terminal of the electric generator, this wire being in electrical connection with the inner end of the block 21 and the wire or wires from the other terminal being in connection with the outer end of said block, or the block may have an opening 25 of larger diameter than the conductor which is centrally supported in the opening by any desired insulating means, or the block may be composed of separated sections and the conductor may occupy a position midway of the space between them, all of these constructions being shown in Fig. 2. The number and shape of the resistance blocks in a hearth may be varied as desired without departing from my invention or the hearths may consist mainly of a series of such resistance blocks mounted at their opposite ends in the wall structure, as shown for instance at 26 in Fig. 4, each block being connected at one end to one terminal of the electric generator and at the opposite end to the other terminal of the same, and the blocks

being, if desired, insulated from one another as, for instance, by an electric insulating material inserted between them, the upper faces of the blocks being covered with a layer 27 of refractory material to provide a proper hearth surface heated from below but the blocks being exposed on their under surfaces so as to radiate heat directly upon the material on the hearth beneath.

In a furnace of the type shown in Fig. 4 the hearth may have a central strip 28 of tile or firebrick for carrying the rabbles 20.

I claim:

1. In a metallurgical furnace having a plurality of superposed hearths, a hearth with electrical resistance body therein exposed on the underside of the hearth so as to radiate heat directly onto the material on the hearth below.

2. A metallurgical furnace having a hearth with electrical resistance body therein, and an electrically insulated conductor passing through said body and in electrical connection with the inner portion thereof.

3. A metallurgical furnace having a hearth composed of a plurality of sections disposed side by side, electrical resistance bodies in some of said sections, and rabbles carried by sections alternating therewith.

4. A metallurgical furnace having a hearth with open-bottomed recess therein, an electrical resistance body contained in said recess and exposed on the under side, and means for passing a current of electricity through said resistance body so as to heat the same.

5. A metallurgical furnace having a hearth with sector-shaped recess therein, a sector-shaped electrical resistance body adapted to said recess, and means for passing a current of electricity through said resistance body so as to heat the same.

6. A metallurgical furnace having a hearth with recess therein, an electrical resistance body contained in said recess, an electrical conductor passing through said resistance body from the outer to the inner portion of the same, and means for insulating said conductor from said resistance body except at the inner portion of the latter.

In testimony whereof, I have signed my name to this specification, in the presence of two subscribing witnesses.

UTLEY WEDGE.
